UNITED STATES PATENT OFFICE.

DELBERT J. MARTIN, OF SACRAMENTO, CALIFORNIA.

MARCEL IRON.

Application filed March 28, 1928. Serial No. 265,296.

This invention relates to hair curling or marcelling irons, my principal object being to provide an iron of this general character so constructed that it will flatten the individual hairs with which it comes in contact, provided of course that the instrument is properly manipulated. The purpose of this is to enable the hair being treated to be given the flat form in cross section which is common to all naturally curly hair, as distinguished from the round form of non-curly hair. By means of my improved iron, therefore, in connection with the use of certain chemicals, I may impart to previously straight hair an actually permanent wave, and this without the use of the expensive equipment now being necessary, and without the iron having to remain engaged with the hair for a great length of time as is now common with the forming of the present so-called permanent waves.

At the same time my iron may be used for ordinary hair curling purposes just as the ordinary hand curling iron is used.

A further object of the invention is to produce a simple and inexpensive device and yet one which will be exceedingly effective for the purpose for which it is designed.

These objects I accomplish by means of such structure and relative arrangement of parts as will fully appear by a perusal of the following specification and claims.

In the drawings similar characters of reference indicate corresponding parts in the several views:

Fig. 1 is a side elevation of my improved iron partly broken out.

Fig. 2 is a cross section of the cooperating jaws in a hair clamping position.

Referring now more particularly to the characters of reference on the drawings, the iron comprises a pair of cooperating jaws A and B which are pivoted together at one end as at 1 and provided with operating handles 2 arranged to be moved together as the jaws approach each other.

The jaw A is the male element and consists of a relatively long rigid spindle 3 provided at the end adjacent the handle with an enlarged shoulder 4 and at its outer end with a short enlarged tip 5, which is preferably cut on a taper toward its outer end and in the direction of the jaw B.

Turnably mounted on the spindle between the shoulder and tip and having a neat run-

ning fit on the spindle is a sleeve 6 forming a roller.

The jaw B is the female jaw element and comprises a substantially semi-circular trough 7, the same length as the jaw A and adapted to receive the latter therein with a slight clearance along the sides. The trough is provided with a slot 8 in the bottom the same length and in the same relative location as the roller 6, into which slot the upper periphery of a roller 9 projects slightly, the roller being the same length as the roller 6. The roller 9 is turnably supported by lugs 10 depending from the jaw B at the ends of the roller. The pivotal connection 1 of the jaws is so disposed relative to the rollers that when the handles are closed, the rollers will bear evenly against each other from end to end, so as to impart equal pressure to all hairs passing between the rollers at any point in the length thereof.

In operation the jaws are spread and the hair to be curled is disposed so it passes across the jaw B. The handles being then closed and brought tightly together causes the rollers to clamp the hair therebetween. A transverse movement is then imparted to the iron as a whole while maintaining the close pressure on the handles. This causes the rollers to turn and they will crush and roll the hairs therebetween so that their shape is changed from a round form in cross section to one of a flat shape without tending to strain or unduly pull the hair. This operation gives the hairs the properties necessary for sustaining a permanent curl or wave, and if the hair is treated at the same time with certain chemicals, such permanency will be assured.

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described my invention what I claim as new and useful and desire to secure by Letters Patent is:

1. A hair curling iron including a pair of cooperating jaws between which the hair to be curled is passed, means for moving the jaws into close relationship with each other, and

- means provided with the jaws for clamping engagement with the individual hairs when pressure is exerted against the jaws to tightly close the same.
- 5 2. A hair curling iron including a pair of cooperating jaws between which the hair to be curled is passed, means for moving the jaws into close relationship with each other, and longitudinally extending rollers mounted 10 in connection with the jaws and between which the hair passes; the rollers moving into close contact with each other from end to end when the jaws are brought together.
3. A hair curling iron including a pair of

cooperating jaws between which the hair to be curled is passed, means for moving the jaws into close relationship with each other, one jaw including a roller, and the other jaw comprising a trough member to receive the roller, and a roller mounted below the trough and projecting throughout its length into the trough through a slot provided in the bottom thereof; said rollers being parallel to and adjacent each other when the jaws are brought together.

25

In testimony whereof I affix my signature.

DELBERT J. MARTIN.
